UNITED STATES PATENT OFFICE.

ADOLPH H. KOCH, OF LOS ANGELES, CALIFORNIA.

DESIGN FOR A GAS-HEATER.

46,478.

Specification for Design.

Patented Sept. 29, 1914.

Application filed August 1, 1914. Serial No. 854,580. Term of patent 7 years.

To all whom it may concern:

Be it known that I, ADOLPH H. KOCH, a citizen of the United States, residing at Los Angeles, in the county of Los Angeles and State of California, have invented a new, original, and ornamental Design for Gas-Heaters, of which the following is a specification, reference being had to the accompanying drawings, forming part thereof.

Figure 1 is a perspective view of one side

of the heater. Fig. 2 is a perspective view of the front of the heater.

I claim:

The ornamental design for a gas heater, as shown.

ADOLPH H. KOCH.

Witnesses:

LORA M. BOWERS,
LORRAINE E. DURROW.
